[57] CLAIM

The ornamental design for a combined vest and carrier for compressed gas cylinders, as shown and described.

DESCRIPTION

FIG. 1 is a front perspective view of a combined vest and carrier for compressed gas cylinders showing my new design;

FIG. 2 is a top rear perspective view thereof;

FIG. 3 is a bottom rear perspective view thereof;

FIG. 4 is a front elevational view thereof;

FIG. 5 is a rear elevational view thereof;

FIG. 6 is a left side elevational view thereof, the broken lines showing a compressed gas cylinder being for illustrative purposes only and forming no part of the claimed design; and,

FIG. 7 is a right side elevational view thereof.

FIG. 1

FIG. 2

FIG. 3

FIG. 4

FIG. 5

FIG. 6

FIG. 7
